D12-203. OR D 11,709 EX

No D 11709 MAR 30, 1880

UNITED STATES PATENT OFFICE.

WALDEN EDDY, ABRAM REYNOLDS, NATHAN S. LANGDON, AND JAMES M. EDDY, OF GREENWICH, NEW YORK.

DESIGN FOR HORSE-BLOCKS.

SPECIFICATION forming part of Design No. 11,709, dated March 30, 1880.

Application filed January 23, 1880. Term of patent 7 years.

To all whom it may concern:

Be it known that we, WALDEN EDDY, ABRAM REYNOLDS, NATHAN S. LANGDON, and JAMES M. EDDY, citizens of the United States, all of Greenwich, in the county of Washington and State of New York, have invented and produced a new and original Design for a Horse-Block, of which the following is a specification, reference being had to the accompanying drawings, forming part thereof.

Figure 1 is a perspective view from the front of our newly-designed horse-block; Fig. 2, also a perspective view of the same from the rear.

Our design, as shown by the accompanying drawings, is in form, when sectioned transversely, of two ordinary steps united together by side or end panels and by front and back panels, the end panels forming guards at the ends of the lower step.

The steps A and B are ornamented by being formed with openings *a* through them, said openings being of diamond form and arranged similarly to the cells of a honey-comb with respect to each other.

The end panels, C and D, are both just alike, and are constructed with openings *b* through them, of the ornamental form represented. The guard portions C' D' of these end panels are formed with ornamental openings *c* through them, as represented. The front and back panels, E, F, and G, are also formed with ornamental openings *d* and *d'* through them, of the form shown in the drawings.

The ornamentations, as shown, partake of 35 the form of scrolls, curves, straight lines, and circles united and combined as shown in the drawings, and these, together with the form of the foundation structure, constitute a tasteful design for a horse-block for use in front of 40 dwellings or in yards where persons require it in mounting upon horses or in getting in and out of carriages.

In the back panel a recess, *g*, is provided, and in the same the name-plate of the occupant of the premises is inserted, so as to be removed whenever another name is required to occupy the recess.

The horse-block is made of cast metal.

What we claim is—

1. The design for a horse-block, as herein shown and described, the same consisting of the two steps A and B, end panels, C C' and D D', and front and rear panels, E, F, and G, and the ornamentations of said panels and 55 steps, as shown in the drawings.

2. The design for a horse-block of the form and ornamentation herein shown and described, and having the name-plate recess *g* in one of the panels, as shown.

WALDEN EDDY.
ABRAM REYNOLDS.
NATHAN S. LANGDON.
JAMES M. EDDY.
